US0D1051122S

(12) **United States Design Patent** (10) Patent No.: **US D1,051,122 S**
(45) Date of Patent: ** Nov. 12, 2024

(54) **ELECTRONIC DEVICE**

- (71) Applicant: **Apple Inc.**, Cupertino, CA (US)
- (72) Inventors: **Bartley K. Andre**, Palo Alto, CA (US); **Matthew Phillip Casebolt**, Fremont, CA (US); **Houtan Farahani**, San Ramon, CA (US); **Ron Alan Hopkinson**, Campbell, CA (US); **Eric Knopf**, Mountain View, CA (US); **Jay Scott Nigen**, Mountain View, CA (US); **Gavin John Reid**, Campbell, CA (US); **Mikael Silvanto**, San Francisco, CA (US); **Richard Hing Tan**, Fremont, CA (US); **Eric Joel Weirshauser**, San Jose, CA (US)
- (73) Assignee: **Apple Inc.**, Cupertino, CA (US)
- (**) Term: **15 Years**
- (21) Appl. No.: **29/743,810**
- (22) Filed: **Jul. 24, 2020**

Related U.S. Application Data

- (63) Continuation of application No. 29/435,191, filed on Oct. 20, 2012, now Pat. No. Des. 901,484.

CLAIM

The ornamental design for an electronic device as shown and described.

DESCRIPTION

The sole FIGURE is a top view of an electronic device showing our new design.

The outline of the elements of the electronic device shown in solid lines is claimed.

The broken lines are for the purpose of illustrating portions of the electronic device that form no part of the claimed design.

1 Claim, 1 Drawing Sheet
